UNITED STATES PATENT OFFICE

ASA LEE RIGHENOUR, OF CHICAGO, ILLINOIS

INTERNAL COMBUSTION ENGINE

Application filed April 2, 1923. Serial No. 266,494.

The present invention relates to improvements in internal combustion engines, and has particular reference to improvements in variable stroke engines of the general type disclosed in my copending application, Serial No. 194,455, filed May 26, 1927, Patent No. 1,728,363, of Sept. 17, 1929.

The engine disclosed in said application comprises an actuating cam for the piston, and means for holding the two yieldingly in operative engagement. The cam is formed with two diametrically opposed lobes having arcuate surfaces adapted to actuate the piston successively for each revolution of the cam in an intake or suction stroke, a compression stroke, a firing stroke, and an exhaust or scavenging stroke. The opposed lobes are unequal in length so that the exhausting and intake strokes are of maximum length, and substantially longer than the compression and firing strokes. The opposed lobes also are shaped to vary the time and rate of movement of the piston in opposite directions. This may be accomplished by forming the opposed cam lobes of different transverse widths, and also by off-setting one of the contact faces on each end of the cam at a greater distance from the longitudinal center of the cam than its opposite face. As a result, the opposite sides of each end of the cam are formed with arcs of different curvatures. By reason of this construction, the cam causes a rapid preliminary movement and a subsequent slower movement of the piston during the scavenging or exhaust stroke; causes the return or suction stroke to be slowly initiated and then accelerated to a greater speed than the maximum speed of the exhaust stroke, thereby resulting in an intense suction action; causes the compression stroke to increase in speed during its first half and then gradually diminish to the end or firing point; and causes the firing stroke to be more rapid than the compression stroke, and then decrease, thereby resulting in the greatest leverage at the beginning of the stroke. The piston will go through one complete cycle of movements for each complete revolution of the cam. The valves are therefore operated directly from the cam shaft and with-

out the use of special timing mechanism and gearing.

By providing a full exhausting stroke and a full intake stroke, the burned gases are completely expelled from the cylinder, and a large, fresh and cool charge is taken in. As a result, no portion of the unburned gases remains to deposit carbon in the cylinder or to cause detonation upon contact with the incoming charge, to dilute and heat the fresh charge, and to lower the compression. Provision need not be made for taking care of high temperatures, and a relatively thin fuel mixture may be used. A high and uniform torque is obtained. By providing an actuating cam for the piston, few mechanical parts are needed. Thus, the motor has no crank-shaft, connecting rod, camshaft, connecting rod bearing, timing gears, water jacket or radiator.

The primary object of the present invention resides in the provision of a novel motor of the above general type having a plurality of piston and cylinder units.

If the cylinders are spaced peripherally about the motor casing, the motor will take up a great deal of space, will be cumbersome and awkward, and will be impracticable for a great many purposes, such as farm use. Other important objects of the present invention therefore reside in the provision of a new and improved motor having a plurality of piston and cylinder units in which the units are grouped at one side of the motor casing, and having means for operating the pistons in uniform sequence.

A further object is to provide a novel multi-cylinder motor in which the cylinders are grouped in a portion of the motor casing, and in which the pistons are adapted to be actuated by a cam having a plurality of peripherally spaced points in a multiple of two, corresponding inversely to that circumferential portion of the casing occupied by the cylinders.

Still another object is to provide a multi-cylinder motor of the above character in which the firing strokes of the pistons overlap so that one of the pistons is in a firing stroke at all times, thereby obtaining a uni-

form torque, reducing vibration, and eliminating dead centers.

A further object is to provide a multi-cylinder motor of the above character in which there will be no knocking, and in which ball-bearings can therefore be used to advantage.

Another object is to provide in a multi-cylinder motor of the above character, of novel means for holding the pistons effectively against the actuating cam.

A more specific object resides in the provision of a novel mechanical restoring device for the pistons which comprises a tape instead of springs, and which maintains a uniform pressure at all the bearing parts, thereby avoiding knocking and hence making the use of ball bearings practicable.

A further object resides in the provision of a novel oiling system for the motor.

A general object resides in the provision of a novel multi-cylinder motor of the above general type which is simple, light and inexpensive in construction, which comprises a relatively small number of parts, which can be readily assembled, disassembled and repaired at a relatively small cost, and which is highly efficient in operation and adapted to a wide range of uses.

Further objects and advantages will become apparent as the description proceeds.

In the accompanying drawings, Figure 1 is a front end view of a motor embodying the features of my invention, the end plate being removed to show the interior.

Fig. 2 is a longitudinal sectional view of the motor taken along line 2—2 of Fig. 1.

Fig. 3 is a transverse sectional view taken along line 3—3 of Fig. 2.

Fig. 4 is a transverse sectional view taken along line 4—4 of Fig. 2.

Fig. 5 is a diagrammatic view of the actuating cam for the pistons.

Fig. 6 is an enlarged sectional view of a detail taken along line 6—6 of Fig. 3.

Fig. 7 is an enlarged fragmentary view in front elevation of the inner end of one of the piston and cylinder units.

Fig. 8 is a fragmentary outer end view of one of the piston and cylinder units.

Fig. 9 is an enlarged fragmentary view of a detail of the piston retaining means.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring more particularly to the drawings, the motor constituting the embodiment

of the invention comprises a suitable casing 10 which may be of any suitable form, and which in the present instance is generally cylindrical in shape to provide a generally cylindrical cam chamber 11. The casing 10 has front and rear end walls 12 and 13 of which the front wall 12 has a removable cover plate 14 normally held in place by means of a plurality of bolts 15. Depending from the body of the casing 10 and opening to the chamber 11 is a hollow base 16 which may be supported by any suitable means (not shown). In the present instance, suitable seats 17 which are adapted to receive and to be secured to parts of the support are provided in opposite sides of the base 16. The casing 10 is suitably ribbed to provide strength and rigidity.

Opening in spaced relation to the cam chamber 11 are a plurality of suitable cylinders. While any desired plurality of cylinders may be provided, in the present instance I have shown six equally spaced cylinders 18, 19, 20, 21, 22 and 23 opening at their inner ends through the peripheral wall 90 of the casing 10. Since these cylinders preferably are alike in construction, but one of them will be described, and corresponding parts of the others will be designated by like reference characters. In the preferred construction, each cylinder is formed separately of the casing 10, and has an outer air cooled end 24 and an inner end 25. The outer end 24 is closed by a suitable head 26 adapted to be secured thereto by means of bolts 27, and the inner end 25 projects through an opening 28 in the peripheral wall of the casing. The cylinder is mounted in position by means of a peripheral flange 29 which is suitably secured to the peripheral margin of the opening 28. Formed in the head 26 are a suitable inlet valve 30 controlling a fuel inlet passage 31 adapted to be connected to a suitable fuel supply (not shown), and a suitable exhaust valve 32 controlling the outlet to the exhaust. The inner end of the cylinder is tapered in its outer surface at its inner edge, as indicated at 33, to bring the inner ends of the cylinders closely together, and is formed in its front and rear sides with two diametrically opposed longitudinal slots 34 and 35, extending from the inner edge substantially to the peripheral wall of the casing 10.

Slidably disposed in the cylinders 18 to 23 respectively are a plurality of suitable pistons 36, 37, 38, 39, 40 and 41. Preferably, the pistons are alike in construction, and hence but one of them will be specifically described, the corresponding parts of the others however, being designated by like reference characters. In the preferred construction, each piston is hollow, and the inner end thereof is formed with two diametrically opposed inwardly extending projections 42 having holes or bores 43 in registration with the

slots 34 and 35. Disposed in the holes 43, and extending at its opposite ends through the slots 34 and 35 is a pin 44. Two cam rollers 45 are suitably mounted on the ends of the pin 44 outside of the cylinder. In the present instance, the cam rollers 45 are mounted on ball bearings 46, and the latter are spaced from the piston by means of spacer sleeves 47 which are secured to the pin 44, and which bear against the sides of the slots 34 and 35. The parts, i.e., the piston, the pin 44, the spacer sleeves 47 and the ball bearings 46 with the cam rollers 45 are held in assembled relation by means of suitable nuts 48 threaded onto the extreme ends of the pin.

The cam rollers 45 are arranged to coact with a suitable cam 49 for actuating the pistons in timed and uniform sequence. In the present instance, the cam 49 comprises two separate but identical plates 49a and 49b rotatably mounted in spaced and coincident relation at opposite sides of the cylinders 18 to 23 for engagement with the cam rollers 45. By providing a double cam and roller mechanism for actuating the pistons, a balanced central thrust is obtained and binding is avoided. Supporting the cam plates 49a and 49b is a suitable shaft 50 from which the power developed by the motor is adapted to be utilized. The shaft 50 is journaled in suitable ball bearings 51 and 52 secured respectively in bearing sleeves 53 and 54 in the end walls 12 and 13 of the casing 10. The sleeve 54 is formed on the end of a central hub 55 which projects outwardly from the rear end wall 13 and which defines a small cylindrical chamber 56 opening to the chamber 11 substantially concentrically about the shaft 50. Preferably, the cam plates 49a and 49b are formed with rearwardly extending hubs 57 and 58 keyed to oppositely flared portions 59 and 60 of the shaft 50, the hub 8 being disposed in the chamber 56. Suitable packing glands 61 and 62 are secured in the outer ends 45 of the sleeves 53 and 54 to close the latter and to seal the bearings for the shaft 50.

If a motor comprises a single piston and cylinder unit, uniform operation can be obtained by means of an actuating cam having two spaced heads. If a motor comprises a plurality of piston and cylinder units uniformly spaced about the entire periphery of the casing, the same cam may be employed to operate the pistons in timed and uniform sequence. Obviously each piston will move through the four strokes of a complete cycle once for each complete revolution of the cam. A motor in which the piston and cylinder units are arranged in uniformly spaced relations about the entire periphery of the casing is impracticable for many purposes, such as farm use. The primary reasons for this are that the motor is bulky and cumbersome, and cannot be mounted satisfactorily on land vehicles, particularly farm vehicles. In the

present invention, I have therefore grouped the piston and cylinder units in a portion of the motor casing, thereby saving in space, and providing a construction adaptable to a large variety of uses, including uses in stationary plants, and in land and air vehicles.

Obviously, any desired number of piston and cylinder units may be provided, and these may be spaced over any desired portion of the casing. In the present instance, as recited in the foregoing, six piston and cylinder units are provided, and these piston and cylinder units are grouped in uniformly spaced relation in the upper half of the casing 10. The end piston and cylinder units are each inclined axially 15° from the horizontal, and adjacent piston and cylinder units are angularly spaced 30°. Obviously, a cam having but two spaced heads would not actuate the piston and cylinder units in uniformly timed sequence since during one half of one revolution each point on the cam, for example the firing point or the exhaust point, would move idly through space. Hence, I have provided a cam 49 having a plurality of peripherally spaced heads in a multiple of two corresponding inversely to that circumferential portion of the casing in which the piston and cylinder units are grouped. In the present instance, the cam 49 is therefore provided with four heads 63, 64, 65 and 66 which preferably are substantially uniformly peripherally spaced, and of which the diametrically opposed heads 63 and 65 are conveniently designated as "firing heads", and the diametrically opposed heads 64 and 66 are conveniently designated as "exhausting heads". It will be evident that as one head leaves the last piston and cylinder unit of the group, the opposite head comes into operative relation to the first piston and cylinder unit. Hence, the piston and cylinder units are actuated in uniformly timed sequence, and each piston goes through a complete cycle twice for each complete revolution of the cam 49.

Each of the cams 63 and 65 has a curved face 67 for moving each piston out on the compression stroke, and a curved face 68 for controlling the movement of the piston on the firing stroke. Each of the cams 64 and 66 has a curved face 69 for moving each piston out on the exhaust stroke, and a curved face 70 for controlling the inward movement of the piston on the intake stroke.

Preferably, the firing cams 63 and 65 are shorter than the cams 64 and 66 so that a variable stroke motor is obtained. As a result, the exhaust stroke and the intake stroke are of maximum length so as to completely exhaust the gases of combustion and to take in a fresh cool and undiluted charge of fuel. The advantages of this construction are numerous. First, the deposition of carbon and detonations, which ordinarily occur through contact between the fresh incoming fuel

charge and the unexpelled gases of combustion, are avoided. A more dilute fuel charge may be used, and still complete and efficient combustion will be obtained. As a result, there will be no partially burned gases and poisons such as carbon monoxide, to be exhausted into the atmosphere. Since no inert gases with the temperature of exhaust are present at the start of the intake stroke, undesirable high temperatures are avoided.

The variable stroke also kills vibration.

Preferably, the cam faces 67, 68, 69 and 70 are so shaped that maximum efficiency is obtained in combustion and in the mechanical development of the power generated. In the present instance, the cam faces are so shaped that on the exhaust stroke the piston has a rapid preliminary movement and then a subsequent slow movement, on the inlet stroke the movement of the piston is initiated slowly and is then accelerated to a speed greater than the maximum speed of the exhaust stroke, on the compression stroke the movement of the piston is increased during the first half and is then gradually diminished, and on the firing stroke the movement of the piston is more rapid than the compression stroke and then decreases. By providing the most rapid movement at the start of the firing stroke, it is obvious that the greatest leverage is obtained at the time when the most power is available.

To obtain continuity of propulsion, the firing faces 67 are of such length that the firing strokes of the pistons overlap, i. e., before the firing stroke of one piston is completed, the firing stroke of another piston is initiated. As a result, dead centers are avoided. In the present instance, the faces 68 and 70 extend on an arc of 35°, and the faces 67 and 69 extend over an arc of 55°. Since the piston and cylinder units are spaced 30° apart, the firing strokes for adjacent pistons and for the end pistons will overlap 5°.

Suitable means is provided for holding the cam rollers 45 continually in contact with the cam 49. Preferably, this means has a mechanical restoring action instead of a spring action. A spring action is not entirely satisfactory since it may weaken and may permit knocking. In the present instance, this means comprises a metallic restoring tape 71 (see Figs. 2 and 3) which engages a fixed retaining structure 72 and each of the pistons, and which is suitably secured at its opposite ends. Preferably, the tape 71 extends alternately over rollers 73 of which one is mounted in the inner end of each piston, and rollers 74 mounted in the structure 72. Seven rollers 74 are provided, and these are arranged in an arc falling well within the innermost points on the cam 49. Successive rollers 73 are disposed in a line extending substantially between successive pairs of the rollers 74. Each of the rollers 73 is rotatably

mounted on the pin 44 between the projections 42 of the piston. The retaining structure 72 preferably comprises a pair of spaced standards 75 which are rigidly connected by spacers 76 to form an integral frame, and the lower ends of which are clamped to a pair of horizontally spaced tubular rods 77 extending through tubular fittings 78 in the front and rear walls of the oil casing 16. The upper ends of the standards 75 are arcuate in form and are disposed about the sleeve 57 of the cam plate 49a. The rollers 74 are suitably mounted on fixed bearing pins 79 secured between the upper ends of the standards 75.

Suitable oiling means is provided. To this end, one of the hollow tubular rods 77 opens to a line 80 adapted to be connected to a suitable source of lubricant (not shown). A tube 81 opens to said rod 77, and extends therefrom upwardly and then about the sleeve 57. The upper curved end of the tube 81 is connected through a plurality of branch tubes 82 to the interior of the bearing pins 79. Each of the latter opens to admit oil where desired.

The ends of the tape 71 are secured to tensioning means in opposite sides of the casing 10 which preferably are alike in construction, and of which but one will be described in detail, corresponding parts of the other however, being designated by like reference numerals. Each tensioning means (see Figs. 3 and 6) comprises a hollow cylindrical casing 83 which is removably secured to one side of the structure 72, and which is inclined upwardly and inwardly at approximately 45° in a tangent line to the end roller 74. The upper end of the casing 83 is partially closed by a ring 84 through which the end of the tape 71 extends, and the lower end opens next to the side of the casing 10 in line with an opening closed by a plug 85 through which access to the tensioning means may be had. Slidably disposed in the casing 83 is a piston 86 carrying an axial stem 87 having a clamp head 88 in which the end of the tape is secured. In the present instance, the clamp head 88 is split longitudinally and has a lateral jaw-shaped opening in its free end. The end of the tape is secured about a wedge 89 in the opening, and the split portions of the head are clamped tightly against the tape by means of a nut 90 threaded onto the head. The head 88 is arranged eccentrically to the stem 87 so that the latter is in alignment with the outwardly extending tape. Disposed between the ring 84 and the piston 86 is a coiled spring 91. The tension of the spring 91 may be suitably adjusted by adjusting the stem 87 in the piston 86. It will be evident that the tensioning means serve to give the strip 71 any desired tension. In normal operation however, the ends of the tape are substantially stationary, since as one piston gives slack

another one takes up slack to the same extent. As a result the retaining means has primarily a mechanical action and not a spring action. By providing a retaining means of this character, the cam rollers 45 are retained securely and continually against the peripheral faces of the cam 49 throughout the complete cycle. As a result, the three pushes and the pull on the piston in the course of each cycle do not result in knocking, i. e., the pressure remains the same with reference to all bearing parts. This makes it practicable to use ball bearings as described thereby obtaining a smooth even operation, and 15 a low oil consumption consummation.

Means is provided for actuating the valves 30 and 32 in timed relation to the reciprocation of the pistons. In the present instance, this means comprises a pair of timing cams 20 92 and 93 mounted on the hub 58 of the cam plate 49b. The cam 92 is adapted to coact with a plurality of radially reciprocatory plungers 94 slidably disposed in bearing sleeves 95 formed in the hub 55 and opening 25 to the periphery of the chamber 56. These plungers are connected respectively to a plurality of rods 96 which in turn are connected to suitable means 97 for actuating the valves 30. Similarly, the cam 93 is adapted to actuate a plurality of plungers 98 slidably disposed in sleeves 99, and connected through rods 100 to suitable means 101 for operating the valves 32. The rods 96 and 100 are suitably enclosed by hollow tubes 102 and the 35 valve actuating mechanisms are suitably enclosed by casings 103, one on each cylinder head 26. The rods 96 and 100 extend in the same radial direction as their respective cylinders. The exhaust cam 92 has a pair of 40 diametrically opposed lugs 104 which are adapted to be moved successively into successive engagement with the plungers 94, and the intake cam 93 has a pair of diametrically opposed lugs 105 which are adapted to be moved into successive engagement with the plungers 98. It will be evident, that as one lug on either cam leaves the last plunger, the other lug on said cam will engage the first plunger. The cam 92 is positioned in advance of the inlet cam 93 so that each exhaust valve opens and closes just ahead of the companion inlet valve 32.

Means is provided for supplying lubricant or oil to the casings 103 for the valve actuating mechanisms. This means comprises an arcuate header 106 connected through a plurality of branch feeder pipes 107 to the casings 103, and through a pipe 108 to one of the tubular rods 77, the other end of said rod being adapted to be connected to a suitable source of supply (not shown). Drip oil collecting in the bottom of the casing 16 may be withdrawn through a suitable opening 109. Because of the provision of a cam for actuating the piston and cylinder units, the

valve cams 92 and 93 can be driven directly with the cam, thereby eliminating timing gears and various other timing mechanism. As a result, an extremely simple, efficient, fool-proof construction is obtained.

The operation will now be briefly described. Assuming that the cam 49 is rotating clockwise as appearing in Fig. 1, the piston 36 is near the end of its exhaust stroke, the piston 37 is at the start of its exhaust stroke, the piston 38 is on its firing stroke, the piston 39 is near the end of its compression stroke, the piston 40 is at the start of its compression stroke, and the piston 41 is at the start of its inlet stroke. As the cam 49 is rotated, each piston will be moved successively through an exhaust stroke, an inlet stroke, a compression stroke and a firing stroke, and will go through two complete cycles for each revolution of the cam. Before the roller on the piston 38 leaves the cam surface 68, the roller on the piston 39 will move onto the cam surface, thereby insuring a continuity of propulsion. A short time before the roller for the piston 41 leaves the cam surface 68 of one of the heads 63 and 65, the roller for the piston 36 will engage the cam surface 67 of the other of the heads 63 and 65. Hence the piston and cylinder units will operate in uniformly timed sequence even though 95 grouped in a portion of the casing.

A variable stroke is obtained. The exhaust strokes are full, thereby completely expelling the burned gases, and hence insuring complete and efficient combustion of the incoming charge. Due to the mechanical restoring means which effectually retains the pistons in operative relation to the cam 49, no knocking results and hence ball bearings can be used to advantage. The construction is simple and compact, and by reason of the grouping of the piston and cylinder units in the upper portion of the casing, may be conveniently and securely mounted on a large variety of stationary and moving plants.

I claim as my invention:

1. In an internal combustion engine, in combination, a casing, a plurality of piston and cylinder units arranged in peripherally spaced relation and grouped in a portion of the periphery of said casing, a shaft, an actuating cam on said shaft, said cam having a plurality of peripherally spaced heads for moving each piston successively in an intake stroke, a compression stroke, a firing stroke, and an exhaust stroke, said heads being of unequal length so that said intake stroke and said exhaust stroke will be substantially longer than said compression stroke and said firing stroke, certain of said heads being similar so as to adapt them to periodically replace each other in operation so as to operate the pistons of said units continuously, retaining means for holding said pistons in operative relation to said cam, means for adjusting said

retaining means, means for oiling said retaining means, inlet and discharge valves for said units, operating mechanisms for said valves, and a pair of timing cams rotatable with said actuating cam to actuate said valves in timed relation to the movements of the pistons.

2. In an internal combustion engine, in combination, a casing, a plurality of piston and cylinder units grouped in a portion of said casing, a shaft, and an actuating cam on said shaft, said actuating cam having a plurality of peripherally spaced actuating heads, the number of heads being a multiple of a number which is the inverse of that circumferential portion of said casing occupied by said units, the pistons of said units being operatively related to said cam.

3. In a device of the class described, in combination, a plurality of piston and cylinder units, a rotary cam, means on the pistons engaging said cam, a stationary retaining structure, a mechanical retaining member extending alternately in engagement with said pistons and said retaining structure to hold said means against said cam.

4. In a device of the class described, in combination, a piston and cylinder unit, a rotary cam, a cam roller carried by the piston and engaging said cam, a retaining structure mounted along-side said cam, said retaining structure having a pair of rollers, a roller mounted in the inner end of said piston, and a retaining tape fixed at its ends and extending over said rollers to hold said cam roller in contact with said cam.

5. In a device of the class described, in combination, a casing, a piston and cylinder unit opening peripherally to said casing, a shaft, a cam on said shaft, said piston having means operatively related to said cam, a retaining structure comprising a pair of vertically spaced standards mounted in said casing, and encircling said shaft, a pair of rollers mounted between said standards and within the innermost circle of revolution of the cam face, a roller mounted in the inner end of said piston, said piston roller being disposed substantially on a line between said rollers on said retaining structure, a retaining tape extending under said retaining rollers and over said piston roller, means for yieldingly securing the ends of said tape, and means for adjusting the tension on said tape.

6. In a device of the class described, in combination, an even number of piston and cylinder units, a rotary cam operatively related to the pistons, a stationary retaining structure, a mechanical retaining member extending alternately in engagement with said retaining structure and the pistons to hold said pistons in operative relation to said cam, means for tensioning said member, said cam being operable to actuate said pis-

tons in timed sequence without materially varying the tension in said member.

7. In a device of the class described, in combination, a casing, a piston and cylinder unit opening to said casing, a shaft, a double cam on said shaft, parts of said cam being disposed on opposite sides of said unit, said piston having a roller and having means operatively related to both parts of said cam, spaced retaining rollers mounted in said casing at opposite sides of said first mentioned roller and means for retaining said first mentioned means and said cam in operative relation, said last mentioned means extending under said retaining rollers and over said first mentioned roller, means for yieldingly securing the ends of said tape, and means for tensioning said tape.

8. In a device of the class described, in combination, a plurality of piston and cylinder units, a rotary cam, means on the pistons engaging said cam, a stationary retaining structure, a retaining member extending alternately in engagement with said pistons and said retaining structure, and spring means yieldingly securing the ends of said member.

9. In a device of the class described, in combination, a casing, a piston and cylinder unit opening peripherally to said casing, a shaft, a cam on said shaft, said cam being double and disposed at opposite sides of said unit, said piston having means on opposite sides operatively related to said cam, a retaining structure comprising a pair of vertically spaced standards mounted between said cam parts in said casing, and encircling said shaft, a pair of rollers mounted between said standards and within the innermost circle of revolution of the cam face, a roller mounted in the inner end of said piston, a retaining member extending under said retaining rollers and over said piston roller, and means for yieldingly securing the ends of said member.

10. In a device of the class described, in combination, a retaining structure comprising a pair of standards, means for holding said standards in spaced relation, a plurality of rollers mounted between said standards, a flexible retaining member engaging said rollers and adapted to be flexed between said rollers, and adjustable means for tensioning said member.

In testimony whereof, I have hereunto affixed my signature.

ASA LEE RIGHTEOUR.
